UNITED STATES PATENT OFFICE.

ROBERT F. DARBY, OF YONKERS, NEW YORK, ASSIGNOR TO AMERICAN STEEL FOUNDRIES, OF CHICAGO, ILLINOIS, A CORPORATION OF NEW JERSEY.

DRAFT MECHANISM.

1,390,675.

Specification of Letters Patent. Patented Sept. 13, 1921.

Application filed June 19, 1919. Serial No. 305,225.

To all whom it may concern:

Be it known that I, ROBERT F. DARBY, a citizen of the United States, residing at Yonkers, in the county of Westchester and 5 State of New York, have invented certain new and useful Improvements in Draft Mechanism, of which the following is a specification.

This invention relates to draft mechanism 10 for railway cars, and more particularly to such mechanism for freight cars.

The present freight cars of the country have been built during the last twenty or twenty-five years. Each individual road has 15 changed its design from time to time as new lots of cars were built. The draft gear manufacturers have made the draft gears to suit themselves or have modified the constructions to suit the individual desire of each 20 railroad. The result is a lack of interchangeability of draft mechanism on cars built at different times by each and every railroad.

In the past railroads have decided on 25 strengthening certain lots of old weak cars, the design was made, the material procured, and the cars ordered home for this purpose.

War operating conditions changed this 30 procedure. No attempt was made to home route cars. A car unloaded on a foreign line was reloaded and shipped to any other foreign line. As a result thereof each railroad company had its freight cars scattered all over the country to a far greater extent 35 than heretofore, with no authority to call its cars home.

This operating condition, together with the multiplicity of design, practically stopped the strengthening of the older cars. 40 Weakness was repaired in kind or an adequate substitution made with as little work as possible. The main object was to keep the car moving.

This situation became serious owing to 45 the great amount of cars damaged and held for repairs. A large percentage of the damaged cars in question have their draft mechanism in bad condition.

Accordingly, one object of my invention 50 is to facilitate the repair of the draft mechanism of freight cars of various conflicting designs.

Another object is to provide simple, durable and efficient draft mechanism adapt-

ed to meet successfully the emergency requirements for repairing freight cars.

These and other objects are accomplished by means of the mechanism shown on the accompanying sheets of drawings, in which—

Figure 1 is a plan view of my universal draft mechanism;

Fig. 2 is a side elevation of the same;

Fig. 3 is a plan view of my draft mechanism, showing a slightly different arrangement from that shown in Fig. 1;

Fig. 4 is a side elevation of the arrangement shown in Fig. 3;

Fig. 5 is an end view, parts being in section, of the arrangement shown in Fig. 1;

Fig. 6 is an end view, parts being in section, of the arrangement shown in Fig. 3;

Fig. 7 is a sectional view taken in the plane of line 7—7 of Fig. 2;

Fig. 8 is a sectional view taken in the plane of line 8—8 of Fig. 4;

Fig. 9 is a sectional view taken in the plane of line 9—9 of Fig. 2; and

Fig. 10 is a sectional view taken in the plane of line 10—10 of Fig. 4.

The various novel features of the invention will be apparent from the following description and drawings and will be particularly pointed out in the appended claims.

It is realized that in making a universal repair of this character it may be necessary to respace the center sills to change the height of the truck bolster center plate, change the trucks under the car, rebend the arch bars, move the body bolster forward or backward, remove the dead wood block, or make other more or less structural changes which, however, it is believed will be a cheaper and quicker repair, looking at the matter only from the point of getting the cars repaired and back into service as quickly as possible.

In the first place, I have arranged for a vertical adjustment of two inches for the draft gear and coupler within the draft arms 10. If it is necessary to make more of a vertical adjustment than two inches in the height of the coupler, it will be necessary to obtain this additional adjustment by raising or lowering the truck bolster, resetting the arch bars, blocking up under the springs, or accomplishing this result in several well known ways. In other words, the

5 pocket in the draft arms 10 is made two inches deeper than ordinarily, so that the draft gear can be used in any horizontal position from the extreme top of the pocket to the extreme bottom of the pocket.

10 This draft gear pocket has been made 27 inches long, which will take about the longest draft gear in service. A great many draft gears are shorter than this. The standard adopted by the U. S. R. R. A. is 24-5/8 inches long. In order to maintain U. S. safety appliance standard spacing between two cars, the front stop will remain the same distance from the front end. If the 27-inch pocket 15 is too long for the old type of gear, the back part of the pocket is to be filled with a block or blocks 11 riveted in place, which will shorten the effective length of the pocket any desired amount.

20 As many of the cars referred to are equipped with tandem springs which require a center stop, I have provided the draft arms 10 with center stop members 12. If some other gear is to be used which does not 25 need the center stop, the center stop may be burned away by means of a gas or electric welding outfit, with which practically all shops are now equipped. It is a very simple and cheap operation to burn away a portion 30 of the casting such as this, by using what is termed a cutting flame or arc, instead of a welding flame or arc. There may be another type of draft gear used which would require holes in the side of the draft gear pocket, 35 and accordingly I have provided the draft arms 10 with a reinforcing bead 13 defining an area within which holes 14 may be cut through the draft arms. Where this hole is necessary, the center stops 12 are not necessary, and, on the other hand, where the center stops are necessary, the hole is not necessary. Therefore, all of the draft arms are 40 provided with cast center stops 12 and with 45 holes, but the draft arms are provided with beads 13 for reinforcing purposes in the event that holes are cut through the arms. When it is desired to use a draft gear requiring the holes 14, the center stop 12 will be burned away and the holes 14 will be 50 burned through the main web of the draft arms at the proper height. By referring to Figs. 7 and 8, it will be noted that the holes 14 are shown at two different heights.

55 The draft gear can be held at the proper height by any one of a number of differently shaped carry irons 14', these carry irons to have an upward set, a downward set, or be straight across, as is necessary to bring the draft gear to the proper vertical height. 60 When a down set carry iron is used for the draft gear to occupy the lowest possible position, there will be too much play between the top side of the draft gear and the under side of the top part of the pocket under certain 65 conditions. In order to hold the draft gear

down and eliminate any undesired play, the draft arms are provided with openings 15 for the reception of a bar 16. When the draft gear is in its highest position, it will not be necessary to use the bar 16. The 70 carry iron having an upward set may be used in accordance with requirements, as shown in Figs. 5 and 9.

75 My arrangement contemplates spacing the draft arms 10 so that the distance between the two forming the draft gear pocket will be 10-7/8 inches wide, as shown in Fig. 9, or 12-7/8 inches wide, as shown in Fig. 10. The 10-7/8-inch width is an old standard used mostly for the tandem spring gear. The 80 12-7/8-inch width is the standard for the majority of friction gears. It may be necessary to pull down the center sills and respace and renail them to get this spacing, or if the sills happen to be too far apart furring 85 blocks can be used on the inside of the sills.

90 In order to hold the draft yoke, which is usually 5 inches wide, from shifting on the back follower, the distance between the two back stops 17 on the draft arms is usually made so as to allow for approximately 1/2-inch play of the yoke. For instance, if the yoke is 5 inches wide, the distance between these two stops when both arms are in place is usually 5-1/2 inches. If the back 95 stops are made the proper depth to give the desired yoke clearance when the pockets are 10-7/8 inches, there would be too much play between these stops when the pocket is 12-7/8 inches wide. Therefore, I propose to 100 make the stops 17 the right height or the right depth for the proper yoke clearance when there is a spacing of 12-7/8 inches, these stops being burned off when the parts are brought closer together to provide a 105 pocket 10-7/8 inches wide.

105 The same is true with respect to the front stops 18 formed at the front end of the draft arms, said stops determining the side motion of the coupler. If these stops are made the 110 right dimension for a 10-7/8-inch spacing, there will be too much side play to the couplers for draft arms spaced from that dimension up to 12-7/8 inches. Accordingly, I have provided front stops 18 to be of the 115 proper dimensions when the draft arms are spaced the maximum distance apart, said stops to be burned off the desired amount when the spacing between the draft arms is made less.

120 In order to give the proper clearance over the top of the coupler at the deadwood, it is proposed to use spacing blocks 19 of the proper thickness when the front carry iron is to be used with the extreme upward set, 125 as shown in Fig. 5.

125 The opening 20 (see Figs. 2 and 4) in the draft arm for the body bolster is made 18-1/8 inches. This is somewhat wider than the average body bolster. This length of open- 130

ing is sufficient to take care of any type of body bolster used, or practically any spacing that might be found from the face of the end sill to the center of the body bolster. 5 In order to bring the body bolster in the proper position with the draft arms, the thickness of the deadwood block also may be slightly varied. As it is impossible and is not the intention that the opening 20 in 10 the bottom of the draft arm over the top of the body bolster should help take the buff and pull, I propose to reinforce the body bolster with deep sub-sills 21 located immediately under the main sills, cut to fit snugly the 15 body bolster. Old car sills may be used for this purpose, as the average railroad shop is plentifully supplied with such sills. I have provided just forward of the body bolster a wide, deep flange 22, against which the forward end of the short piece of sub-sill 21 is 20 to bear. This sub-sill is to be bolted transversely to the draft arms and vertically through the main sill. The end of this short sub-sill is to be cut to the proper shape to 25 conform with the front side of the body bolster, so that there will be a deep bearing against same to prevent turning movement. Ordinarily, the sub-sills to the rear of the body bolster are only 4 inches deep. I propose to make same 8 inches deep, as this is 30 the usual depth of the old sill.

It will be noted that the carrier irons 14' for both the coupler and draft gear are offset as shown and are reversible to vary the 35 height of the center line of draft.

By means of the draft mechanism shown on the drawings and hereinabove described, it is possible to repair draft mechanism of freight cars, the design of which varies 40 greatly, said universal draft mechanism having parts which may be readily inserted and removed in accordance with requirements.

It is my intention to cover all modifications of the invention falling within the spirit and scope of the following claims.

I claim:

1. In draft mechanism for railway cars, draft arms having a center stop formed 50 thereon to coöperate with tandem springs when such are used, said draft arms also having reinforcing beads defining spaces within which openings may be formed in said draft arms for operatively receiving a 55 different form of draft rigging, the beads

being adapted to compensate for whatever material may be sacrificed in forming said openings.

2. In draft mechanism for railway cars, draft arms having a center stop formed 60 thereon to coöperate with parts of one type of draft rigging when such draft rigging is used, said arms also being provided with strengthening beads defining areas within which openings may be formed in said draft arms for operatively receiving a different form of draft rigging, the center stop to be removed and the openings provided when one type of gear is to be used and the center stop to remain in place and no gear supporting openings formed in the draft arms when another type of draft gear is to be used, the beads being adapted to compensate for whatever material may be sacrificed in forming said openings. 75

3. In draft mechanism for railway cars, draft arms having a center stop formed thereon to coöperate with parts of one type of draft rigging when such draft rigging is used, said arms also being provided with 80 strengthening beads defining areas within which openings may be formed in said draft arms for operatively receiving a different form of draft rigging, and front and rear stop members on said draft arms, the dimensions of which may be varied in accordance with different conditions, the beads being adapted to compensate for whatever material may be sacrificed in forming said openings. 85

4. An emergency draft mechanism which may be applied to any type of car and within which any type of draft mechanism may be mounted, said draft mechanism including draft arms having center stops formed on the inner surfaces thereof to coöperate with tandem springs when such are used, said draft arms also having reinforcing beads formed on the outer surfaces thereof defining spaces within which openings may be 90 formed in said draft arms for operatively receiving a different form of draft rigging, the area defined by said beads being greater than the area of the openings which may be formed in the draft arms, for the purposes 100 intended. 105

Signed at New York, New York, this 14th day of June, 1919.

ROBERT F. DARBY. 110
